TUBULAR CHIME

Fred Mason, Covington, Ky., assignor to NuTone
Chimes Inc., New York, N. Y., a corporation of
New York

Application March 14, 1939, Serial No. 261,784

3 Claims. (Cl. 116—169)

This invention relates to chimes of the type comprising a vibratable, tubular chime or sound-
ing element, and a striker for vibrating it. The
striker is either of the mechanical type or one
comprising a plunger and solenoid electro-mag-
netically operable by a push button switch. The
chime element itself is an elongated tube which
when struck vibrates to produce a resonant
sound.

10 The primary object has been to provide a tu-
bular chime element which is capable of provid-
ing sounds of a fuller and more pleasant tone
when struck, than the chime elements which
heretofore have been available.

15 With few, if any exceptions, the sounds pro-
duced by the typical tubular chimes have been
comprised of overtones of a brassy, metallic and
very undesirable character. One of the principal
20 features of the present invention resides in the
improvement of the quality and tonal value of
the sound of the chime element.

Another object of the invention has been to
improve the arrangement of the chime elements
and the strikers for operating them. In using
25 the conventional chime elements, it has been very
difficult to position two solenoid strikers so that
both strike the tube at some point which proves
most efficient for sound production. In some
30 instances the strikers are located radially around
the tube adjacent the upper end of it. This ar-
rangement, however, makes it necessary to have
a bulky and large cover to house the chime oper-
ating mechanism. If the striker units are placed
35 side by side, with their cores parallel to one an-
other, then one of them can be positioned to
strike the tube at a nodal point, but not both.
Neither is it effective or convenient to angulate
the strikers relative to one another so that their
40 axes converge at a nodal point. The present in-
vention contemplates a structure in which the
solenoid strikers may be spaced adjacent one
another, so that they do not necessarily strike the
same point, without impairing the quality of the
45 sound produced from the chime or the volume
of it.

It is also very desirable that the electromag-
netic striker units be operable upon the six-volt
50 electric current furnished by the ordinary door-
bell ringing transformers usually installed in the
homes. The chime tubes themselves, however,
are relatively heavy; consequently sharp, quite
powerful impact blows upon them are required
55 for full development of the sound. When the
usual electromagnetic strikers are operated upon

six volts the blows which they deliver tend to be,
or are too feeble for the purpose.

To overcome this disadvantage the object has
been to provide a tubular chime element which is
capable of developing a full resonant tone even 5
when operated upon voltages furnished from
conventional doorbell ringing transformers or
similar means.

The present invention is based upon the dis-
covery that a pronounced improvement in the 10
tone quality and the volume of sound produced
by a chime is obtained when a prong or rod-like
anvil is provided at the end of the chime tube
for receiving the striking blows. This anvil is
mounted rigidly upon the tube, or is made as an 15
integral part of it, and projects axially beyond
the end of the tube for the reception of blows
either from one or a series of strikers disposed
at various points along its length. When this
20 anvil is struck instead of the tube then full reso-
nant tones are produced from the chime and no
metallic overtones or harsh sounds are developed.
The sound produced by the instrument is notice-
ably different, both qualitatively and quantitively,
25 from the sound produced from a chime tube
of the conventional structure. The sound de-
veloped by the chime does not vary as the anvil
is struck at different points upon its length.
This characteristic enables two solenoid strikers
30 to be placed side by side for operating upon the
anvil without variation in the volume of sound
or purity of its tone. Moreover, the volume of
sound produced from a relatively feeble blow up-
on the anvil, for example, a blow from a solenoid
35 operated upon six-volt current, is at least equal
to, and in most cases much greater than the
sound produced from a striker operated from an
eight or fourteen volt transformer and arranged
to strike the tube in the conventional manner.

Other objectives and further features of the in-
vention are disclosed in the description which
40 follows.

A preferred embodiment of the invention is
shown in the accompanying drawing in which:

Figure 1 is a front elevation of a chime unit 45
embodimenting two chime tubes.

Figure 2 is a side elevation.

Figure 3 is a top plan view.

The chime of Figure 1 embodies a base 2
upon which hangers 3—3 are mounted. These 50
hangers are comprised respectively of arms 4—4
which are in spaced parallel relationship and
serve to spread the strings 5—5 from which the
chime tubes are suspended. The upper edges of
the hangers preferably contain notches 6 in 55

spaced relationship for holding the support strings 5—5 in predetermined positions.

The chime tubes are designated generally at 1. Each tube is of elongated form and is made of 5 metal, preferably brass. The tubes, as shown, are open at their lower ends though they may contain caps or closures. At the upper end each tube contains an anvil indicated generally at 8.

In the preferred structure the anvil of each 10 tube is comprised of an elastic portion 9. This preferably is of rod-like nature and it terminates in a plug portion 10 engaging the end portion of the tube. It is requisite that the anvils be affixed tightly to the tubes; loose connections give 15 rise to the production of harsh metallic sounds when the anvils are struck.

The anvil may be constructed several ways without departing from the spirit of the invention. The rod portion of the anvil is integral 20 with the plug, or it may be press-fitted into the plug, as shown in the drawings. Alternatively, it may be sweated on by solder or held in the plug by threaded connection. Likewise, the plug can be held in its position inside of the chime 25 tube in any of these ways, or the anvil may be made in one piece and fastened into the tube as above described. The anvil elements also may embrace the tubes in exterior connection instead of being fitted within the interior of them.

30 The portion 9 of the anvil is of sufficient length to accommodate the various strikers from which it is to receive blows along the length, and it preferably is of relatively slender configuration, to facilitate compactness in the structure and 35 avoid the use of wide spreaders for keeping the support strings from contacting the anvil and dampening the sound vibrations. However, other supporting structures may be employed in place of the one which is illustrated. The anvils 40 are preferably made of steel or brass, and may be round, as shown, or square, or of other suitable shape. The rod portions of the anvils are bored as at 11 to receive the support strings 5.

45 The chime tube is operated by applying a lateral impact blow upon the anvil. In the device shown in Figure 1 a striking mechanism is of a typical arrangement and embodies solenoids 12 and 13 supported from the base 2 by means 50 of the bracket 14. The solenoids 12 and 13 contain sleeves 15 and 16 within which plungers 17 and 18, shown in the phantom lines in Figure 1, are slidable. The plungers carry non-metallic hammer heads. These preferably are of wood 55 or felt, or leather, to avoid the production of metallic sounds.

The base 2 of the device contains terminals 19, 20 and 21. The terminals of the solenoids are connected to the leads in the conventional

manner and the terminals in turn are in electrical connection with the appropriate signal buttons energized from a six-volt battery, or a six-volt transformer or the like.

One of the sleeves, 15, of the solenoid is closed 5 at one end so that the plunger is free to move in one direction only. This sleeve contains an appropriate spring abutment for retracting the plunger within the sleeve upon deenergization 10 of the solenoid. The other sleeve is open at both ends and the plunger of it contains a hammer head at each end. This plunger is free to be projected in one direction to strike one of the anvils and a spring (not shown) is located within 15 the sleeve to retract it and cause it to rebound through the sleeve and be impact against the other end of it. This phase of the structure, disclosed in Figure 1, is conventional and need not be described here in detail.

20 In place of the striking mechanism which is shown other types of electromagnetic strikers, including swinging hammers and the like, may be employed. Those skilled in the art will understand that the invention is not limited to the foregoing description of a typical embodiment 25 but only by the claims which follow.

Having described my invention, I claim:

1. A sounding device, comprising a chime tube, a metallic member comprising a slender elongated portion which is of lesser diameter than the tube, attached to the tube at one end thereof with the slender portion extending substantially axially from the end of the tube, said member including means for suspending the tube, said slender portion comprising an anvil element which, upon being struck, is adapted to sound 30 said chime tube.

2. A sounding device, comprising a chime tube, a metallic anvil member comprising an anvil which is of lesser diameter than the tube, the anvil member being attached to an end of the tube with the anvil extending substantially axially from the end of the tube, and means for supporting the tube from the anvil member, the anvil of said anvil member being of sufficient 40 length to be struck by several hammer devices disposed along its length.

3. A sounding device, comprising a chime tube, a metallic member comprising a slender elongated portion which is of lesser diameter than the tube attached to the tube at one end thereof with the slender portion extending substantially axially from the end of the tube, said slender portion comprising an anvil element which, upon being struck, is adapted to chime 50 said chime tube.

FRED MASON.
